UNITED STATES PATENT OFFICE.

KUNO BAUERSCHMIDT, OF KARLSHORST, GERMANY, ASSIGNOR TO GENERAL ELECTRIC COMPANY, A CORPORATION OF NEW YORK.

ELECTRIC SWITCH.

Application filed April 7, 1925, Serial No. 21,320, and in Germany May 3, 1924.

My invention relates to improvements in electric switches and more particularly isolating or disconnecting switches especially for high potentials.

5 The size and consequently the weight of insulators for disconnecting switches depend on the potential of the circuit and since the static properties of the insulators most commonly used are better adapted for compression than tension, torsion and bending, it is highly desirable that these latter stresses be eliminated or at least reduced to a minimum. Moreover, it is important for space economy and safety that the striking distance between 10 the contacts when the switch is open be a maximum for a minimum spacing between conductors.

An object of my invention is to provide an improved electric switch in which the static 20 properties of the insulators are utilized to the best advantage and in which a safe arcing distance between the contacts of the switch in the circuit open position thereof is obtained without so decreasing the arcing distance between phase conductors as to necessitate a great increase in the spacing thereof.

My invention will be better understood from the following description taken in connection with the accompanying drawing and 30 its scope will be pointed out in the appended claims.

In the accompanying drawing Fig. 1 is an elevation of an electric switch embodying my invention; Fig. 2 is a plan of the switch shown in Fig. 1; Fig. 3 is a part sectional view on the line 3—3 of Fig. 2; and Fig. 4 is a plan of a modification of the embodiment of my invention shown in Figs. 1 and 2.

Referring now to the several figures of the drawing, a plurality of stationary supporting members, such as two substantially parallel insulators 10 and 11, are mounted on a suitable framework which may comprise longitudinal and transverse structural members such as channels 12 and 13, and plates 14. The insulators 10 and 11 support line terminals 15 and 16 respectively, and one of the insulators 10 supports a suitable contact 17. Cooperating with the contact 17 is a contact 18 which is mounted on a suitable support such as a movable insulator 19. This insulator is arranged for revolution about an axis intermediate the insulators 10 and 11, so as to actuate the contact 18 from a position adjacent insulator 10 to a position adjacent in-

sulator 11, indicated by the dot and dash lines, in the circuit opening movement of the switch and vice versa. For this purpose, the insulator 19 is mounted on one end of a crank 20 which is rigidly secured to a shaft 21 rotatably mounted on the supporting framework.

The axis of revolution of the insulator 19, that is the shaft 21, may be substantially parallel to, and is preferably substantially equidistant from the insulators 10 and 11 in order to obtain the maximum distance between the contacts 17 and 18 in the circuit open position of the switch. The axis of the shaft 21 may be coplanar with the axes of both of the insulators 10 and 11, as illustrated in Fig. 2, or offset from the plane of the axes of the insulators 10 and 11 as illustrated in Fig. 4. The distance between the movable insulator 19 and its axis of revolution, the shaft 21, or in other words, the length of the crank 20, may be approximately equal to one-half of the distance between the insulators 10 and 11 in order to get the maximum contact separation without the necessity of unduly spreading the phase conductors. For the same purpose, and also for stiffness, the contact 18 may be relatively short.

It will be obvious that with the arrangement shown in Fig. 2, the arcing distance between conductors is reduced in the maximum transverse displacement of the contact 18 only by approximately one-half the throw of the contact 18, while in the full open position the contact 18 is so positioned as not to decrease the effective arcing distance between phase conductors when a plurality of switches are employed side by side in the respective phase conductors. With the arrangement shown in Fig. 4, the arcing distance between conductors is reduced still less, since the maximum transverse displacement of the movable insulator 19 from the plane of the axes of the insulators 10 and 11 is considerably less than the length of the crank 20.

In either case, since the movable insulator does not have to transmit motion by rotation about its own axis, it is not submitted to torsion and the bending stresses induced on contact separation and closure are relatively small.

In order to insure correct alignment of the contacts 17 and 18 for circuit closing, a guide plate 22 having a sloping face may be mounted as shown in detail in Fig. 3. This plate is

arranged so that the insulator supporting end of the crank 20 rides up on the sloping face of the plate as the contact 18 is moved to circuit closing position.

5. For conducting current from the stationary insulator 11 to the movable insulator 19, an articulated connection comprising links 23 and 24 may be used or these may serve merely to support a flexible conductor which carries 10 the current. For obtaining the necessary freedom or universality of movement, the links 23 and 24 are connected to each other at one end and at the other end to the supports 11 and 19 respectively by any suitable means 15 such as swivel mountings or universal joints, examples of which are known to the art.

What I claim as new and desire to secure by Letters Patent of the United States is:—

1. An electric switch comprising two stationary line terminal supports, a contact mounted on one of said supports, a cooperating movable contact and means for actuating said movable contact to and from circuit closing position with the stationary contact, comprising a support having its axis substantially parallel to the stationary supports and mounted for revolution about an axis intermediate said stationary supports from a position adjacent one of them to a position adjacent the other.

2. An electric switch comprising two substantially parallel stationary line terminal supports, a contact mounted on one of said supports, a cooperating movable contact, and 35 means for actuating said movable contact to and from circuit closing position with the stationary contact, comprising a support mounted for revolution about an axis intermediate of and substantially parallel to said stationary supports from a position adjacent one of them to a position adjacent the other.

3. An electric switch comprising two stationary line terminal supports, a contact mounted on one of said supports, a cooperating movable contact, and means for actuating said movable contact to and from circuit closing position with the stationary contact comprising a support mounted for movement about an axis substantially parallel to and 50 equidistant from said stationary supports from a position adjacent one of them to a position adjacent the other.

4. An electric switch comprising two sub-

stantially parallel stationary line terminal supports, a contact mounted on one of said supports, a cooperating movable contact, and means for actuating said movable contact to and from circuit closing position with the stationary contact comprising a support mounted for revolution about an axis substantially parallel to and equidistant from said stationary supports from a position adjacent one of them to a position adjacent the other.

5. An electric switch comprising two stationary substantially parallel line terminal insulators, a contact mounted on one of said insulators, a cooperating contact, means for supporting and actuating said cooperating contact to and from circuit closing position with said stationary contact comprising an insulator mounted for revolution about an axis offset from the plane of the axes of said stationary insulators and equidistant therefrom from a position adjacent one of them to a position adjacent the other.

6. An electric switch comprising two stationary substantially parallel line terminal insulators, a contact mounted on one of said insulators, a cooperating contact and means 80 for supporting and actuating said cooperating contact comprising an insulator mounted for revolution about an axis offset from the plane of the axes of said stationary insulators and equidistant therefrom from a position adjacent one of them to a position adjacent the other through an angle of approximately 180°.

7. An electric switch comprising two substantially parallel stationary line terminal supports, relatively movable cooperating contacts, one being mounted on one of said supports, means for actuating the other of said contacts to and from circuit closing position with the stationary contact comprising a support mounted for revolution about an axis substantially parallel to and equidistant from said stationary supports from a position adjacent one of them to a position adjacent the other, and an articulated connection between said movable support and one of the stationary supports.

In witness whereof, I have hereunto set my hand this 18th day of March, 1925.

KUNO BAUERSCHMIDT
